Application May 4, 1945, Serial No. 119,399

Term of patent 3½ years

(Cl. D29—20)

To all whom it may concern:

Be it known that I, Lily Mark Tolpo, a citizen of the United States, residing at Chicago, in the county of Cook and State of Illinois, have invented a new, original, and ornamental Design for Frame for Mirrors, Pictures, and the like, of which the following is a specification, reference being had to the accompanying drawing forming part thereof.

In the drawing:

I claim:

The ornamental design for a frame for mirrors, pictures, and the like, as shown.

LILY MARK TOLPO.
